(57) **CLAIM**

The ornamental design for a handheld case assembly, as shown and described.

DESCRIPTION

FIG. 1 is a front perspective view illustrating my design for a handheld case assembly;

FIG. 2 is a rear perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken, dashed line disclosures depict environmental structure and are for illustrative purposes only. They do not form part of the claimed design.
